CLAIM

The ornamental design for a cabinet, as shown and described.

DESCRIPTION

FIG. 1 is a top, front, right side perspective view of a cabinet showing the new design according to a first embodiment; FIG. 2 is a bottom, rear, left side perspective view thereof; FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top, front, right side perspective view of a cabinet showing the new design according to a second embodiment; FIG. 10 is a bottom, rear, left side perspective view thereof; FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in the drawings depict portions of the cabinet that form no part of the claimed design.

1 Claim, 16 Drawing Sheets
